US0D1072947S

(12) **United States Design Patent** (10) **Patent No.:** **US D1,072,947 S**
(45) **Date of Patent:** **** Apr. 29, 2025**

(54) **GAMING MACHINE AND DISPLAY**

(71) Applicant: **ARISTOCRAT TECHNOLOGIES AUSTRALIA PTY LIMITED**, North Ryde (AU)

(72) Inventor: **Bruce Edward Urban**, Las Vegas, NV (US)

(73) Assignee: **Aristocrat Technologies Australia Pty Limited**, North Ryde (AU)

(**) Term: **15 Years**

(21) Appl. No.: **29/919,082**

(22) Filed: **Dec. 1, 2023**

Primary Examiner — Ryan Harvey

(74) Attorney, Agent, or Firm — Armstrong Teasdale LLP

(57) **CLAIM**

The ornamental design for a gaming machine and display, as shown and described.

DESCRIPTION

(60) Division of application No. 29/708,522, filed on Oct. 7, 2019, now Pat. No. Des. 1,014,633, which is a continuation of application No. 29/619,620, filed on Sep. 29, 2017, now Pat. No. Des. 887,496.

(51) **LOC (15) Cl.** 21-03

(52) **U.S. Cl.**

USPC **D21/369**

(58) **Field of Classification Search**

USPC D21/369, 370, 325
CPC A63F 13/2145; A63F 13/25; G07F 17/322
See application file for complete search history.

D424,122 S	5/2000	Dickenson
D429,769 S	8/2000	Luciano, Jr.

FIG. 1 is a perspective view of a first embodiment of a gaming machine and display in accordance with the new design.

FIG. 2 is a left side view of the gaming machine and display shown in FIG. 1.

FIG. 3 is a right side view of the gaming machine and display shown in FIG. 1.

FIG. 4 is a top view of the gaming machine and display shown in FIG. 1.

FIG. 5 is a perspective view of a second embodiment of a gaming machine and display in accordance with the new design.

FIG. 6 is a left side view of the gaming machine and display shown in FIG. 5.

FIG. 7 is a right side view of the gaming machine and display shown in FIG. 5; and,

FIG. 8 is a top view of the gaming machine and display shown in FIG. 5.

The broken lines showing portions of the gaming machine and display form no part of the claim.

1 Claim, 8 Drawing Sheets
